COMBINED PNEUMATIC SUSPENSION SPRING AND SHOCK ABSORBER FOR A VEHICLE

William Armstrong, Eastgate, Beverley, England, assignor
to Armstrong Patents Co. Limited, Beverley, England,
a British company

Application December 6, 1957, Serial No. 48,820

Claims priority, application Great Britain October 5, 1957

Term of patent 14 years

(Cl. D14—25)

-FIG. 5-

Fig. 1 is a rear elevation of a combined pneumatic suspension spring and shock absorber for a vehicle embodying my new design;

Fig. 2 is a side elevation thereof as seen from the right of Fig. 1;

Fig. 3 is a perspective view thereof;

Fig. 4 is a top plan view thereof; and

Fig. 5 is a bottom plan view thereof.

I claim:

The ornamental design for a combined pneumatic suspension spring and shock absorber for a vehicle, substantially as shown.
